UNITED STATES PATENT OFFICE

GIOVANNI BIGNAMI, OF MILAN, ITALY

APPARATUS FOR SKINNING ANIMALS

Application filed June 23, 1931, Serial No. 546,393, and in Italy June 25, 1930.

The invention relates to improvements in the construction of apparatus for skinning animals and more particularly to the type in which a rotary cutting blade, revolving in a frame provided with a comb to protect the skin during the operation, is driven by a flexible transmission shaft connected to a suitable motor.

These improvements relate to the construction of the annular blade, to the mounting of the blade in the apparatus, to the means for securing the flexible transmission shaft both to the apparatus and to the motive means, and to a mode of construction of the motor support.

According to the invention the knife of the apparatus is formed by a series of small blades or knives, for example of the type employed in safety razors, suitably modified, which are slipped into a circular holder and secured therein by screws or other means.

The circular holder is integral with a ring comprising a toothed crown and forming the movable part of a ball bearing the construction of which is very simple, as will be seen from the following description.

Similarly the devices for securing the flexible shaft both to the apparatus and to the motor are very simple and adapted to permit the flexible shaft to be taken up when it has become stretched through use.

An embodiment of the present invention is illustrated by way of example in the accompanying drawings, in which:

Figure 1 is a side view of the complete apparatus.

Figure 2 shows the same apparatus in plan.

Figs. 3 and 3a are fragmentary top and bottom plan views, respectively, of the cutting element removed from the frame.

Figure 4 is a section taken along the line 4-4 in Figure 2.

Figures 5 and 6 are a side view and a plan of the haversack for containing the motor.

Figures 7 and 8 are details of the tooth point.

Fig. 9 is a sectional detail of the coupling between the flexible drive shaft and the drive motor.

As will be seen from the figures, the skin-

ning device comprises a frame formed of an upper half 12" and a lower half 12' removably secured together by screws 35 between which is rotatably mounted the knife. The knife is formed by a series of small blades 1 having a straight cutting edge; these blades are arranged side by side in such a way as to form a polygonal periphery. The blades are such as to leave between their points of contact the smallest possible angle or no angle at all, and the blades are mounted in an interchangeable manner on a ring 2 having a horizontal groove 3 on its periphery in which the inner part of the blade 1, which is suitably shaped, is slipped and held in place, if desired with the interposition of a packing piece 4, by means of simple set screws 6 passing through open tapped holes 5 in the upper part of the blade carrying ring 2.

If during use one or more blades 1 become broken or dull they may be removed and changed very easily by releasing the screws 6 corresponding to the blades 1 which have to be changed.

Similarly, the blades can be sharpened very easily when they have been removed from the apparatus.

The ring 2 forms the movable part of the ball bearing; the remaining part of the latter comprises a fixed part 9 which is lodged in a corresponding recess in the frame 12'-12". Both the part 2 and the part 9 are grooved at 7 and 8 respectively; these notches are situated opposite each other so as to form a seating for the balls 10. The balls are suitably spaced apart by means of a central ring 11 comprising fork shaped projections 12 directed upwards and curved at the upper part (see Figure 4) so as to enclose the balls which in this way cannot move with respect to each other or slip out at the top.

It is easy to understand that in this way the part 9 of the ball ring will form with the aid of the balls 10 a unit with the part 2 so that, when it is desired to clean the apparatus, the whole arrangement formed by the blade carrying ring and the ring 9 can be removed from the apparatus as a unit.

The ring 2 is provided below with the

toothed crown 13 having radial teeth inclined from the centre to the periphery.

Such an arrangement permits the shaft of the bevel pinion 14 to be arranged at a very small angle with respect to the operating plane of the apparatus, thus avoiding the necessity of providing reduction gearing and permitting a motor to be employed having a high speed of revolution.

10 The shaft of the pinion 14 is mounted upon a ball bearing in the tubular end 15 of the part 12' of the frame.

15 The teeth 37 of the front curved portion of the part 12' of the frame have a specially designed shape which permits the natural elasticity of the skin to be fully employed. A section taken along a vertical plane is formed by two curves connected together (Figures 7 and 8) the terminal curve of which (end 20 of the teeth) 16 is of infinitely smaller radius than the following curve 17. Such a form prevents the teeth from penetrating into the skin and tearing or damaging the latter on account of the form of the tooth itself shown 25 in plan view in Figure 8.

20 The connection between the motor and the flexible shaft (Figure 9) is obtained by means of a screwed sleeve 24 in which is screwed the last part of the flexible tube which is 25 screw threaded; this permits the tube to be shortened or lengthened according to the shortening or lengthening of the flexible drive of the transmission proper 25 which is coupled to the shaft of the motor by means 30 of the tapped sleeve 26 which is mounted upon a screwed tail piece keyed upon the shaft of the motor. The screw must be oppositely threaded with relation to the direction of rotation of the motor as is obvious.

35 The connection between the apparatus and the flexible shaft is obtained by means of the head 26' of the screw 27 (Figure 4) which is connected to the end of the flexible shaft itself, which is provided for this purpose at its 40 end with the sleeve 28, while the outer cover is connected by means of the tap head 29 to the end piece 15 of the apparatus. Naturally, a ball bearing 29' is provided.

45 By such an arrangement it is quite easy to separate the apparatus from the flexible shaft and at the same time it is also easy to remove the flexible shaft 25 from its tube for eventual replacement.

50 Figures 5 and 6 show the support for the electric motor placed in a haversack, which is formed by a base plate 18 provided with cushions 19 and straps 20. The motor 21 is mounted by means of a cross pivot by a fork 22 which can turn about its pivot 23. The 55 motor can when mounted in the manner described be moved easily in all directions without interfering with the operation of the tool.

What I claim is:

1. An apparatus for skinning animals, 60 comprising a flexible transmission shaft,

means for driving said shaft, a frame, a ring rotatably mounted in said frame and operably connected with the transmission shaft, and a knife mounted in said ring and formed of a plurality of separate individually detachable 70 blades arranged side by side and providing a continuous cutting edge of polygonal form, and means for detachably securing each separate blade to the ring.

2. An apparatus for skinning animals 75 comprising a flexible transmission shaft, an electric motor for driving said shaft, a connection between the motor and the shaft, a knife carrying frame comprising an upper member and a lower member having comb teeth over a portion of its periphery, a peripherally grooved ring rotatable between said frame members and operably connected with the transmission shaft, a plurality of knife blades having a straight cutting edge and an arcuate root engaged in said groove so as to form a knife having a polygonal periphery, a packing piece over each separate blade and screws passing through the packing pieces, and blades, whereby said blades are detachably secured to said ring.

3. Apparatus according to claim 2 wherein the rotatable ring forms the outer race of a ball bearing and coacts with an inner race rigidly mounted in the frame, a cage being interposed between these races and having lodgements wherein balls are retained by suitable means.

4. Apparatus according to claim 2, wherein the rotatable ring carries a crown of radial 100 teeth inclined from the outside towards the centre of the apparatus, the said crown of teeth being situated at the lower part of the ring.

5. Apparatus according to claim 2, where- 105 in the teeth in horizontal section have a rounded tip and in depth have a profile formed by an upper surface engaging with the knife blades and a lower surface formed by a curve of small radius at the tip and of 110 large radius thereafter.

In testimony whereof I have signed my name to this specification.

GIOVANNI BIGNAMI.
